HIGH TEMPERATURE SATURATING OR
COATING APPARATUS

Harry A. Cumfer, Glen Ellyn, Ill.

Application November 7, 1935, Serial No. 48,665

16 Claims. (Cl. 91—46)

This invention relates to high temperature saturating or coating apparatus intended for any materials, and especially to apparatus suitable for the manufacture of roofing by saturating and coating roofing paper or felt with a bituminous material such as asphalt.

The fundamental object of the invention is to provide a relatively inexpensive saturating and coating unit capable of handling asphalt or other such materials at the high temperature necessary. It has long been the practice to manufacture roofing by running felt through a saturating vat, between squeeze rolls, through a coating vat, between additional squeeze rolls and then under a sprinkling trough where it is surfaced with a granular material such as crushed slate, after which it is cooled and cut to the desired sizes. The saturating and coating units used heretofore have been quite expensive, partly because of the large number of loops extending down into the saturating bath through which the felt had to run to be sufficiently saturated, and partly because of the necessity for heating the squeeze rolls at a temperature much higher than that of low pressure steam, thus requiring expensive high pressure or superheating steam boiler equipment.

According to the present invention, the cost of this unit is very greatly decreased in two ways. The first is by reducing the number of loops in the saturating vat by providing long upward loops which make unnecessary some of the loops formerly extending downwardly into the saturating vat. The second reduction in cost is obtained by dispensing with the expensive steam boiler equipment and instead using the molten asphalt for heating the various squeeze rolls. This asphalt which is supplied to the saturating vat by a melting tank, may be pumped successively through the squeeze rolls and back either into the vat or into the melting tank to be re-heated. The asphalt in the saturating tank is usually kept at a temperature of from 400° to 450° F., and that in the coating tank is usually kept at a temperature of about 300° F. Thus if the asphalt is drawn from the saturating vat, its temperature is adequate for heating the squeeze rolls. The expense, the inconvenience, and the danger of steam systems are all eliminated. Furthermore, although of course more fuel will have to be used for heating the asphalt than if it were not circulated, yet a fuel economy will result, since it is more efficient to heat the asphalt a little more than to heat an entirely separate steam boiler system.

Other objects and advantages of my invention will be apparent from the following description, taken with the drawings, in which:

Fig. 1 is a partially diagrammatic side elevation of the saturating and coating unit chosen for illustration of this invention.

Fig. 2 is a partially diagrammatic vertical transverse section through the saturating unit, including the melting tank therefor, and showing this invention applied thereto.

Fig. 3 is a view of the saturating unit corresponding with Fig. 1, but showing the gate rolls in position for threading the felt therethrough.

Fig. 4 is a perspective diagrammatic view illustrating particularly the preferred circulation of the hot asphalt through the squeeze rolls.

Fig. 5 is a sectional view through the coating tank of a modification of the invention, in which the asphalt in the coating tank is kept hot by the circulating asphalt from the saturating tank.

Although this invention may take numerous forms, only one form, together with a slight modification thereof, has been chosen for illustration. For the purpose of explaining the invention, it may be assumed that it is being used for manufacturing roofing, although of course it could be used for making wax paper or other materials. The treatment of the felt 11 is the same with or without the modification. From a suitable source of supply such as the roll 12, it passes over a roller 13, under and around a gate roller 14 in the saturating vat 15, over and around a gate roller 16, and around any desired number of successive pairs of rollers 14 and 16, and through squeeze rollers 21 and 22 which are geared together and suitably driven to draw the felt through the saturator. The positioning of these rolls may be regulated by a handle 23 in any desired manner.

From the squeeze rolls 21 and 22 the felt passes over the idler roll 26, down into the coating vat 27, and around the idler gate roll 28 and between squeeze rolls 29 and 30. From there the felt passes through the surfacing, cooling and cutting apparatus which, being conventional, has not been shown. As the felt is drawn up out of the asphalt from the first roll 14, one or both of its surfaces are preferably scraped with adjustable doctor blades 33 to remove the asphalt therefrom so as to facilitate the escape of steam if the felt supplied to the machine is not sufficiently dry to make this unnecessary.

The gate rolls 14 and 16 are suitably supported on gates 36 which are supported for vertical movement and include rack portions 37. The

rack portions 31 of each pair of gates preferably engage a pinion 38 which operates the two gates simultaneously, raising the roll 16 and lowering the roll 14, or vice versa. When the parts are in the position shown in Fig. 3, the felt may be threaded straight between the rollers 14 and 16 to the feed rolls. The handles 39 are then turned to lower the rolls 14 and raise the rolls 16 to the position shown in Fig. 1, unless for special reasons it is preferred that the roller 14 be positioned only part way down in the tank. Any suitable means may be provided for locking the handle 39 or the pinion 38 to secure the gates and the rollers thereon in any desired position.

15 In like manner the felt may be threaded through the coating unit in the same way by raising the gate roll 28 to a position where it will be convenient to thread the felt under it.

The saturating vat is supplied with hot asphalt from a melting and heating tank 41 which is heated by a suitable furnace 42 which may desirably include an oil burner 43. When the asphalt has been heated to the desired temperature, say 400° or 450° F., the valve 44 may be raised, permitting the asphalt to flow through the pipe 46 into the saturating vat 15 where it is kept at the desired temperature by a furnace 47 which may include an oil burner 48. Heretofore the depth of the asphalt in the vat 15 has been regulated by manual control of the valve 44, but according to the present invention it is controlled automatically by a float 51 which operates the valve 44 in any manner desired, as by the lever and linkage system illustrated, in which the pivots 52 and 53 are fixed pivots, being secured to any suitable supports, and the pivots 54 are merely pivotal connections between the moving parts of the system. The burner may be regulated automatically or by hand to maintain the asphalt at the desired temperature.

40 A similar melting tank 56 may be provided for the coating vat 27, being heated by a furnace as illustrated in Fig. 2, and the same valve control being preferred. The vat 27 may be heated by a furnace including an oil burner 48' or by special means described hereinafter.

45 According to the present invention the various squeeze rolls 21—22 and 29—30, and any other elements which require heating, and for which burners are not provided, may be heated by circulation of hot asphalt. As seen best in Fig. 2, a pump 61 is provided for circulating the asphalt, being driven by any suitable motor 62. The pump is preferably a gear pump immersed in the saturating tank 15. In any event, it draws the asphalt from said tank and pumps it through a pipe 63 to whatever elements require heating.

50 In Fig. 2 the pipe 63 is connected to the lower squeeze roll 21 through a suitable stuffing box 64, such stuffing box being provided for all connections between pipes and rolls. From the roll 21 the asphalt flows through pipe 66 to roll 22, and from that it flows through the pipe 67 to such other elements as are to be heated, and 55 through the pipe 68 to the melting tank 41, the dotted lines between the pipe 67 and the piping 68 indicating that there may be additional elements connected between the two. As a matter of fact, in the preferred form of the invention there would be additional elements connected 60 between the two, since, as shown in Fig. 4, the pipe 67 is connected to the lower squeeze roll 29 at the coating tank, which is connected to the upper squeeze roll 30, which in turn is connected 65 to the pipe 68.

As shown in Fig. 5, the asphalt in the coating vat 27 may be heated by asphalt pumped from the saturating vat 15 through the pipe 67 or a separate pipe, to the heating coils 71, and from the heating coils 71 to the rollers 29 and 30 or 5 directly to the melting tank 41. Of course, if the coating vat 27 is heated in this manner the burner 48' shown below this vat in Fig. 1 may be omitted. However, when the burner 48' is provided as shown in Fig. 1, the hot asphalt from 10 the vat 27 may be used for heating certain elements. For example, it may be preferred in some instances to heat the squeeze rolls 21 and 22 with the contents of the vat 15, and to heat the squeeze rolls 29 and 30 with the contents of the 15 vat 27 pumped to said squeeze rolls by a pump similar to the pump 61, but located in the vat 27.

It is not necessary that the asphalt be pumped from the vats to the melting tanks, as it could be pumped back into the vats, or from the saturating vat to the coating vat or its melting tank. Likewise the asphalt flowing from the melting tank to its associated vat could pass through the rolls. The illustrated arrangement is preferred because it permits accurate control of temperature in the vat, and the pump may be used to empty the vat whenever desired. Furthermore, it will permit dispensing with the burner under the saturating vat in some instances. It would even be possible to get along on a single 30 main burner, especially if small control burners were provided.

It is of course desirable to be able to drain all of the asphalt from the various pipes or at least enough so that after a shut-down during which 35 any remaining asphalt is solidified there will be a passage entirely through the pipes so that hot asphalt may be circulated therethrough and melt any remaining solidified asphalt. To this end the circulation is preferably from the lower roll 40 to the upper roll of each pair of rolls, and the lower roll 29 of the coating tank is preferably an inch or so higher than the upper roll 22 of the saturating tank. Likewise all of the piping 68 is 45 preferably inclined so as to drain naturally.

The squeeze rolls have been illustrated as of the so-called solid type, with a relatively small bore therethrough so that substantially all of the asphalt would drain therefrom. As a matter of fact, they might be of the hollow shell type, since 50 in any event they would drain to the level of the inlet and outlet, so that hot asphalt could be pumped through them, melting whatever cold asphalt was retained in the roll. If the coils shown in Fig. 5 are used, a capped or plugged 55 draining outlet 73 should be provided, and of course in any event air inlets may be provided wherever necessary to permit drainage of the pipes. Drainage outlets may also be provided for the two vats, although this is not necessary. The 60 vats may be nearly emptied by pumping the contents thereof into the respective melting tanks and whatever asphalt is left in these vats during the shut-down may be kept warm if the shut-down is for a short time, or may be re-melted if 65 the shut-down is for a longer time.

The foregoing apparatus saves the cost of a separate steam generating and superheating system for heating the various squeeze rolls, and furthermore saves a large part of the cost of operating the same. The provision in the saturating unit of successive rolls, one immersed in the vat and the other high above the vat over which the felt runs, gives the asphalt plenty of time to soak into the felt, with a relatively small number 75

of loops extending into the vat, and consequently a relatively small saturating unit. The double gate construction for raising and lowering these rolls avoids any difficulties which would otherwise be attendant upon their use. The provision of doctor blades for scraping the felt fairly clean as it first comes out of the saturating vat, avoids the necessity for pre-drying the felt, although of course it is still desirable to have it fairly dry.

5 Although but one embodiment of my invention is herein shown and described, it is to be understood that I am not limited thereby, but limit my invention only by the scope of the appended claims. The particular elements heated by the 10 circulating asphalt are illustrative, as other elements such as preheating or reheating rolls or coils located anywhere adjacent the path, if such other elements should be desirable, or any other elements requiring heating, could be heated by 15 the circulating asphalt.

20 I claim:

1. High temperature saturating apparatus including a saturating vat for holding the saturant, means for passing the material to be saturated therethrough including a roll engaging said material after it passes through said saturant, means for heating said saturant, and means for passing some of said heated saturant through said roll.

2. High temperature saturating apparatus including container means for holding the saturant including a saturating vat, means for heating the saturant in said container means, means for passing the material to be saturated through said vat including a roll engaging said material after 35 it passes through said vat, and means for passing said heated saturant from said vat through said roll and back into said container means.

3. High temperature saturating apparatus including a saturating vat for holding the saturant, means for passing the material to be saturated therethrough, means for heating said saturant and means for circulating some of said heated saturant through a member along the path of said material after it leaves said vat to use its heat 45 in the treatment thereof.

4. High temperature saturating apparatus including a saturating vat for holding the saturant, means for passing the material to be saturated therethrough, means for heating said saturant and means for circulating some of said heated saturant through a member along the path of said material to use its heat in the treatment thereof.

5. High temperature saturating apparatus including a saturating vat for holding the saturant, a heating tank for supplying heated saturant to said vat, means for passing the material to be saturated through said vat including a roll engaging said material after it passes through said saturant, means for heating said saturant in said vat, and means for passing said heated saturant from said vat through said roll and into said heating tank.

6. Apparatus for manufacturing roofing including a saturating vat, a melting tank for supplying hot asphalt thereto, a coating vat, squeeze rolls at said saturating vat and at said coating vat, and means for circulating hot asphalt from said saturating vat through the squeeze rolls at 60 said saturating vat, and thereafter through the squeeze rolls at said coating vat and into said melting tank to be reheated for said saturating vat.

7. Apparatus for manufacturing roofing including a saturating vat, means for heating saturant

for said vat, a coating vat, squeeze rolls at said saturating vat and at said coating vat, and means for circulating hot saturant from said saturating vat through the squeeze rolls at said saturating vat and thereafter through the squeeze rolls at 5 said coating vat.

8. Apparatus for manufacturing roofing including a saturating vat, means for heating saturant for said vat, a coating vat, squeeze rolls at said saturating vat and at said coating vat, and means 10 for circulating hot saturant from said saturating vat through the squeeze rolls at said saturating vat and thereafter through the squeeze rolls at said coating vat, said means also causing said saturant to flow through heating pipes in heat 15 exchange relation with said coating vat for heating the saturant therein.

9. Apparatus for manufacturing roofing including a saturating vat, means for heating saturant for said vat, a coating vat, squeeze rolls at said 20 saturating vat and at said coating vat, and means for circulating hot saturant from said saturating vat through heating pipes in heat exchange relation with said coating vat for heating the saturant therein.

10. High temperature saturating apparatus including a saturating tank for holding the saturant, a heating tank for supplying heated saturant to said saturating tank, means for passing the material to be saturated through said saturating tank including a roll engaging said material after it passes through said saturant, and means for causing hot saturant to flow from one of said tanks through said roll to the other of said tanks.

11. Saturating apparatus for roofing, including a vat for holding molten asphalt, a lower roll submerged in said vat, and an upper roll located high above said vat, means for causing roofing material to pass successively around said submerged roll and around said upper roll and into said vat again, said upper roll supporting an upwardly extending loop of material for giving the asphalt time to better saturate said felt for a given total length of time it is submerged in the 45 saturant, said rolls being mounted on gates having racks thereon, and a pinion engaging said racks, and means to rotate said pinion to simultaneously move the upper roll down and the lower roll up until they have passed one another.

12. Saturating apparatus for roofing, including vat means for holding molten asphalt, means maintaining the asphalt at a temperature suitable for saturation, a lower roll submerged in said vat means, an upper roll located high above said 55 vat means, means for causing roofing material to pass successively around said submerged roll and around said upper roll and into said vat means again, said upper roll supporting an upwardly extending loop of material for giving the asphalt 60 time to better saturate said material for a given total length of time it is submerged in the saturant, and scraping means positioned closely above the saturant, contacting one side of said material and removing substantially all of the asphalt 65 from a surface of the material while leaving a surplus of asphalt therein as it first leaves the asphalt in the vat means, to release any steam in said material whereby the material may be more completely saturated on its return to said vat 70 means.

13. High temperature saturating apparatus including a vat for holding a viscous material, means for passing a strip material therethrough, means for heating said viscous material and 75

- means for circulating some of said heated viscous material through a member along the path of said strip material to use its heat in the treatment thereof.
- 5 14. The method of heating rolls for drawing a strip of material through a hot saturating bath which comprises circulating some of the hot saturant through said rolls.
15. High temperature saturating apparatus including a vat for holding a viscous material, means for passing a strip material therethrough, means for heating said viscous material and
- means for circulating some of said heated viscous material through a member along the path of said strip material to use its heat in the treatment thereof.
16. Apparatus for manufacturing roofing including a saturating vat, means for heating saturant for said vat, a coating vat, and means for circulating hot saturant from said saturating vat through heating pipes in heat exchange relation with said coating vat for heating the saturant therein.

HARRY A. CUMFER.
